UNITED STATES PATENT OFFICE.

GEORGE W. KORN, OF NEW YORK, N. Y.

CORK-TURNER.

SPECIFICATION forming part of Letters Patent No. 283,900, dated August 28, 1883.

Application filed October 9, 1882. (No model.)

To all whom it may concern:

Be it known that I, GEORGE W. KORN, a citizen of the United States, residing at the city of New York, in the State of New York, 5 have invented certain Improvements in Cork-Turners, of which the following is the specification.

The nature and object of my invention is to produce a simple and efficient cork-turner for 10 removing corks from bottles, as will hereinafter appear.

Figure 1 is an upright view of the upper part of a bottle with cork in position and the cork-turner inserted and in position to remove the cork. Fig. 2 shows the cork-turner open, with dotted lines in the handle to show the manner of closing it.

This cork-turner is designed to open and close like an ordinary pocket-knife.

20 Similar letters of reference refer to similar parts in the two drawings.

A is the bottle, having the cork B inserted in position.

E is the handle, having the facilities for a 25 knife-blade to close therein.

K is the cork-turner, fastened to the handle E in the same manner as an ordinary knife-blade, and capable of being closed within the handle, as shown by the dotted lines in Fig. 2.

30 C is the longer and D is the shorter arm of the cork-turner. The longer arm, C, is made curvilinear in form, as shown in Fig. 2, the extreme end terminating in a sharp point, or substantially a sharp point. On the inner side of the longer arm C is the shoulder I.

To remove a cork with this cork-turner, the longer arm C is inserted between the cork and inner surface of the neck of the bottle. At the same time the shorter arm D enters the cork at or near the center thereof. The shoulder I 40 passes below the cork and engages with the cork at some point between the two ends of the cork. The cork-turner is now turned slowly by taking hold of the handle E, and by the act of turning the cork is slowly worked 45 out of the neck of the bottle.

The advantage in using this cork-turner to remove corks over other means used is as follows: As the long arm C is forced into position an opening is made, through which carbonic-acid gas or other gases can escape without the overflow incident to suddenly pulling the cork out. The breaking of the cork is also obviated, as the long arm C passes down beside the entire length of the cork, and as 55 the turning takes place the entire length of the cork is moved.

I claim—

As a new article of manufacture, a cork-turner for the purpose of removing corks 60 from bottles, consisting of two arms, C and D, attached to a suitable handle, as and for the purpose shown and described.

GEORGE W. KORN.
